UNITED STATES PATENT OFFICE.

WILLIAM H. MARTIN, OF NEW YORK, N. Y., ASSIGNOR TO AMERICAN TELEPHONE AND TELEGRAPH COMPANY, A CORPORATION OF NEW YORK.

SIGNALING CIRCUIT.

Application filed January 26, 1921. Serial No. 440,127.

To all whom it may concern:

Be it known that I, WILLIAM H. MARTIN, residing at New York, in the county of Bronx and State of New York, have invented certain Improvements in Signaling Circuits, of which the following is a specification.

This invention relates to circuit arrangements for signaling systems wherein signals may be either transmitted from or received at the same station. In its more specific aspects, this invention is embodied in a subscriber's telephone station hereinafter termed, in accordance with the common usage, a substation, and, more particularly, in the combination of a substation and a telephone line, the substation circuit arrangement being of the general type proposed by George A. Campbell and described in a number of U. S. patents issued to him under date of January 22, 1918 and numbered as follows: 1,254,116; 1,254,117; 1,254,118; 1,254,471; 1,254,472; 1,254,473; 1,254,474; 1,254,475 and 1,254,476.

As fully set forth in the patents above referred to, telephone substations of the Campbell type comprise a transmitter receiver, auxiliary resistance and a transformer having a plurality of windings, and these elements, in combination with a telephone line, are so designed that: (1) the transmitter and receiver are conjugate, that is, there is negligible side tone in the receiver in consequence of the actuation of the transmitter by sound waves; (2) the line and auxiliary resistance are conjugate, in order that none of the energy absorbed by the substation from the line shall be wasted in said auxiliary resistance; (3) for a given line having a definite impedance, telephonic energy delivered by the transmitter is a maximum; (4) the amount of energy delivered by the line to the substation is a maximum—in other words, the impedance of the substation as seen from the line is equal to the impedance of the line; (5) at a small sacrifice of efficiency, it is possible to discriminate effectively against disturbing line noise, as distinguished from the telephonic signals from the communicating station.

In common battery telephone exchanges, special conditions often arise in which it is desirable to connect to the switchboard subscribers who are further away from the

office than can be reached with the gauges of cable usually employed for substation loops, without exceeding the standard of transmission maintained for such exchanges. In such cases, in order to reduce the transmission loss between the substations and the switchboard, it is desirable that local battery sets be installed, so that these stations employ local battery for talking and common battery for signaling. It is also desirable that, if local battery sets are to be employed, high efficiency transmitters and receivers should be used, since the use of these instruments in a local battery set would not only give a gain in transmitting efficiency but in receiving efficiency. If, therefore, a set be employed, using a high efficiency transmitter and a receiver of the well-known electromagnet or direct current type, the circuit will not only have the advantages just stated, but it will also be an improvement from a maintenance standpoint, since the local battery set used on extraordinarily long common battery lines will then employ the same transmitter and receiver which are used in the ordinary common battery sets.

It is, therefore, one of the objects of this invention to produce a substation circuit having the characteristics of the Campbell type and which is so arranged that a local battery may be employed to energize both the transmitter and receiver, said local battery being adapted to energize these instruments either alone or in conjunction with common battery energy supplied from a central station, common battery being also employed for purposes of signaling and supervision.

Other and further objects of the invention will be clear from the following description, when read in connection with the accompanying drawing, Figure 1 of which is a schematic diagram of the general type of Campbell substation circuit from which the circuit of the present invention is derived; Fig. 2 of which is a similar diagram of the circuit of the present invention; Fig. 3 of which is a diagram showing the substation circuit of the present invention in more detail; and Figs. 4 and 5 of which are diagrams illustrating the flow of alternating current during the operations of transmitting and receiving, respectively.

The general theory of substations of the

type to which the present invention belongs, is fully set forth in the above mentioned patents to George A. Campbell, so that it is unnecessary to present any theoretical considerations in the present instance, a simple description of the circuit arrangement being sufficient for a full understanding of the invention.

Referring to Figs. 2 and 3, L designates a transmission line terminating in a telephone substation arrangement comprising a transmitter T, a receiver R, an auxiliary resistance X and a transformer comprising windings N₁, N₂ and N₃. One side of the line L and one terminal of the receiver R and the auxiliary resistance X are joined together at a common point 1. The winding N₂ is joined between the other terminal of the line L and the other terminal of the receiver R, the windings N₁ and N₃ being connected in series between the terminals 3 and 4 of the receiver R and auxiliary resistance X. The transmitter T is connected between the common point 5 of the windings N₁ and N₃ and the terminal 3 of the winding N₂ so as to be in shunt with the winding N₁. A local battery B is inserted in series with the winding N₁ for supplying the transmitter current. This battery would also supply an energizing current for the electromagnet receiver R through the windings N₁, N₃ and through the auxiliary resistance X. The resistance of this circuit, however, is quite high and, in order to provide a path of low resistance for the battery supply of the electromagnet receiver R, an impedance coil P is connected between the right-hand terminal of the battery B and the terminal 1'. The impedance coil P is of low resistance so that a large current supply is furnished to the electro-magnet receiver R, but the inductance of the coil P is very high so that, as far as the flow of alternating current in the substation circuit is concerned, the path through the impedance coil is practically an open circuit. The resistance coil P is so proportioned as to supply optimum direct current to the electromagnet receiver R.

The operation of the circuit when transmitting will be as indicated in Fig. 4, in which the arrows designate the instantaneous flow of alternating current. The diagram of Fig. 4 is simplified by omitting the direct current apparatus and illustrating only the circuits for the flow of alternating current. When the transmitter T is actuated, its operation is equivalent to setting up an alternating electro-motive force in the circuit of the transmitter T, so that a current I₁ will flow at a given instant in the direction indicated by the arrow to the right of the transmitter T. As the transmitter T and the receiver R are conjugate, no current flows through the receiver R in

response to the actuation of the transmitter T and, therefore, the current I₄, which flows over the line L, in response to the actuation of the transmitter T, must be equal to the current I₃ flowing through the auxiliary resistance X. Consequently a current equal to the difference between the transmitter current I₁, and the line current or its equivalent the current I₃ through the auxiliary resistance X, appears in the winding N₁ so that a current I₄—I₁ flows in the direction indicated by the arrow just below the winding N₁.

The operation during reception of signals is indicated in Fig. 5. An alternating electromotive force applied to the line L, causes the line current I₄ to flow through the winding of the coil N₂ in the direction indicated. As the auxiliary resistance X is conjugate with respect to the line L under these conditions, no current flows through the said auxiliary resistance and, consequently, no current flows through the winding N₃. It follows, therefore, that the transmitter T is in effect in a local circuit with the winding N₁, and the current I₂ flowing through the receiver R will be equal to the line current I₄. The induced current I₁ in the transmitter circuit will flow through the transmitter and the winding N₁ in the direction indicated.

The circuit above described is a development of the Campbell type of substation disclosed in Fig. 1 of Campbell Patent 1,254,472, above referred to. This type of circuit is indicated schematically in Fig. 1 and in the operation of a circuit of the type shown, in order that it may operate as an anti-side tone circuit, it is necessary that in all cases the voltages between the terminals 2—3 and 3—4 be series-aiding and of the relative magnitude y, where y is the energy distribution ratio and may be defined as the ratio of the energy in the transmitter to the energy in the receiver on receiving.

The design formulæ for the type of circuit of Fig. 1 as given in the Campbell patent just referred to are as follows:

$$\begin{aligned} N_2 &= \pm \sqrt{\frac{R_4}{R_1}} \frac{y}{1+y} \\ N_3 &= \pm \sqrt{\frac{R_4}{R_1}} \frac{1}{y(1+y)} \\ R_s &= \frac{1}{y} R_4 \\ R_2 &= \frac{1}{1+y} R_s \end{aligned} \quad (1)$$

The circuit of the present invention may be obtained from the general type circuit disclosed in Fig. 1 by eliminating the winding N₁ of Fig. 1 and bridging the transmitter T across the terminal 3 and some point 5 of the

winding N_3 . This leads to an auto-transformer arrangement between the windings N_1 and N_3 as shown schematically in Fig. 2. In this figure the part of winding N_3 of Fig. 1 between the terminals 3 and 5 is replaced by the winding N_1 . The windings N_1 and N_2 in Fig. 2 correspond respectively to windings N_1 and N_2 of the circuit of Fig. 1 and the number of turns effectively in series between the terminals 3 and 4 represent the winding N_3 of Fig. 1. These turns and the turns of the winding N_2 of Fig. 2 are always series-aiding as above pointed out.

In general there are a number of possible values of N_3 in Fig. 2, depending upon several possible arrangements of the windings on the core. For example, if all the windings are series-aiding, then the turns of winding N_3 of Fig. 2 will have a value equal to the turns of winding N_3 of Fig. 1 minus the turns of winding N_1 of said figure. If the windings are so arranged that windings N_2 and N_3 of Fig. 2 are aiding and winding N_1 is opposing, then the turns of winding N_3 of Fig. 2 will be equal to the sum of the turns of windings N_3 and N_1 of Fig. 1. If windings N_1 and N_2 of Fig. 2 are aiding and N_3 is opposing then the turns of winding N_3 of Fig. 2 will be equal to the turns of N_1 of Fig. 1 minus the turns of N_2 of Fig. 1.

In practice, when the transmitter is of low resistance, the first of these arrangements is preferable, as it requires a minimum number of turns on the transformer. For this arrangement, the design formulæ may be readily obtained from design formulæ (1), by considering the relation between the units of Fig. 1 and Fig. 2 as just given. These design formulæ will be as follows:

$$\begin{aligned} \frac{N_2}{N_1} &= \sqrt{\frac{R_4}{R_1} \frac{y}{1+y}} \\ \frac{N_3}{N_1} &= \sqrt{\frac{R_4}{R_1} \frac{1}{y(1+y)}} - 1 \\ R_3 &= \frac{1}{y} R_4 \quad (2) \\ R_2 &= \frac{1}{1+y} R_4 \end{aligned}$$

In equations (1) and (2) it will be understood that R_1 is the resistance of the transmitter, R_2 the resistance of the receiver, R_3 the resistance of the auxiliary circuit and R_4 the resistance of the line, while y is the energy ratio previously defined. It is apparent from these formulæ that having given the line resistance and the resistance of the transmitter it is desired to use, the resistance of the receiver and auxiliary element, as well as the number of turns of the winding of the transformer, may readily be obtained by assigning any desired value to the ratio y . As pointed out in the Campbell

patent, a desirable value of y is in the neighborhood of 1.4. It will of course be obvious that while the auxiliary element X is illustrated as a separate resistance element, in practice the resistance represented by this element may be obtained by properly designing the winding N_3 of Fig. 3 so that the elements N_3 and X may be merged.

It will be apparent that the general principles herein disclosed may be embodied in many other organizations widely different from those illustrated, without departing from the invention, as defined in the following claims:

What is claimed is:

1. In a signaling system, a transmission circuit, a transmitting circuit, a receiving circuit, a balancing circuit, and a transformer having three windings, one of said windings being included in said transmission circuit, another of said windings being included in said balancing circuit, and the third winding being included between said transmission and balancing circuits; a terminal of each of said transmission, receiving, and balancing circuits being joined together, the other terminal of said receiving circuit being connected between said third winding and the circuit including one of the other two windings; said transmitting circuit being connected in shunt with said third winding; a source of direct current so connected as to supply current to both said transmitting and said receiving circuits, and a circuit having large impedance and low resistance directly connected to one terminal of said source and to a terminal of said receiving circuit.

2. In a signaling system, a transmission circuit, a transmitting circuit, a receiving circuit, a balancing circuit, and a transformer having three windings, one of said windings being included in said transmission circuit, another of said windings being included in said balancing circuit, and the third winding being included between said transmission and balancing circuits; a terminal of each of said transmission, receiving, and balancing circuits being joined together, the other terminal of said receiving circuit being connected between said third winding and the circuit including one of the other two windings; said transmitting circuit being connected in shunt with said third winding; a source of direct current included in series with said third winding, and a circuit having large impedance and low resistance directly connected to one terminal of said source and to a terminal of said receiving circuit.

3. In a signaling system, a transmission circuit, a transmitting circuit, a receiving circuit, a balancing circuit, and a transformer having three windings, one of said windings being included in said transmis-

6. In a signaling system a transmission circuit, a transmitting circuit, a receiving circuit, a balancing circuit, and a transformer having three windings, one of said windings being included in said transmission circuit, another of said windings being included in said balancing circuit, and the third winding being included between said transmission and balancing circuits; a terminal of each of said transmission, receiving, and balancing circuits being joined together, the other terminal of said receiving circuit being connected to the junction point between said third winding and said transmission circuit; said transmitting circuit being connected in shunt with said third winding; a source of direct current included in series with said third winding, and a circuit having large impedance and low resistance directly connected to one terminal of said source and to a terminal of said receiving circuit.

7. In a signaling system a transmission circuit, a transmitting circuit, a receiving circuit, a balancing circuit, and a transformer having three windings, one of said windings being included in said transmission circuit, another of said windings being included in said balancing circuit, and the third winding being included between said transmission and balancing circuits; a terminal of each of said transmission, receiving, and balancing circuits being joined together, the other terminal of said receiving circuit being connected to the junction point between said third winding and said transmission circuit; said transmitting circuit being connected in shunt with said third winding; a source of direct current so connected as to supply current to both said transmitting and receiving circuits, and a circuit of high impedance but low resistance directly connected to one terminal of said source and to the terminal of said receiving circuit which is joined to said transmission and balancing circuits. 110

8. In a signaling system a transmission circuit, a transmitting circuit, a receiving circuit, a balancing circuit, and a transformer having three windings, one of said windings being included in said transmission circuit, another of said windings being included in said balancing circuit, and the third winding being included between said transmission and balancing circuits; a terminal of each of said transmission, receiving, and balancing circuits being joined together, the other terminal of said receiving circuit being connected to the junction point between said third winding and said transmission circuit; said transmitting circuit being connected in shunt with said third winding; a source of direct current included in series with said third winding, and a circuit of high impedance but low resistance 115 120 125 130

directly connected to one terminal of said source and to the terminal of said receiving circuit which is joined to said transmission and balancing circuits.

5. 9. In a signaling system, a transmission circuit over which direct current supply may be furnished from a central station, a transmitting circuit, a receiving circuit, a balancing circuit and a transformer having three 10 windings, one of the windings being included in said transmission circuit, another of said windings being included in said balancing circuit and a third winding being included between said transmission and balancing circuits; a terminal of each of said transmission, receiving, and balancing circuits being joined together, the other terminal of said receiving circuit being connected between said third winding and the

circuit including one of the other two windings; said transmitting circuit being connected in shunt with said third winding; a local source of direct current so connected as to supply current to both said transmitting and receiving circuits; the circuit being so arranged that direct current transmitted from a central station over said transmission circuit is used for common battery supervision and signaling, while said direct current is used together with the locally supplied direct current for energizing the transmitter and receiver for talking purposes.

In testimony whereof, I have signed my name to this specification this 22nd day of 35 January 1921.

WILLIAM H. MARTIN.
